ELECTRIC PLUG

John Francis Minard, Mount Vernon, Ohio

Application May 10, 1949, Serial No. 92,410

2 Claims. (Cl. 173—361)

1

This invention relates to an electric plug, and more particularly to an electric plug having a novel means for securing the wires of an electric cord to the connecting prongs or blades.

It is an object of this invention to provide an electric plug of the kind to be more particularly described hereinafter, formed for ready insertion of the electric wires of a cord and for readily securing the wires to the connecting prongs or blades.

Another object of this invention is to provide an electric plug of this kind having a latch or locking means for securing the wedge terminals in their wire-engaging position to prevent the accidental or inadvertent disengagement of the wires from the terminals.

Still another object of this invention is to provide an electric plug having swingable contact clamping members mounted in the body of the plug for securely clamping the wires to the prongs and a cover member for the plug having depending lugs or arms engageable with the clamping members in their closed position for holding the clamping members or wedges against swinging to an open position, thereby securely holding the wires clamped to the terminals.

With the above and other objects in view, my invention consists in the arrangement, combination and details of construction disclosed in the drawings and specification, and then more particularly pointed out in the appended claims.

In the drawings:

Figure 1 is a top plan view, with the cover removed, showing one of the clamping elements in its closed, clamping position and the other in its open, wire-receiving position, the depending members of the cover engageable with the clamping elements in their closed position being shown in dotted lines in clamping engagement with one of the wire-clamping wedges;

Figure 2 is a transverse section taken on the line 2—2 of Figure 1, with the cover engaged over the open end of the body;

Figure 3 is a bottom perspective view of the insulated cover removed from the electric plug;

Figure 4 is a bottom perspective view of one of the clamping members removed from the plug;

Figure 5 is a transverse section taken on the line 5—5 of Figure 4;

Figure 6 is an enlarged perspective view of one of the connecting prongs or blades and contact plates removed from the assembly;

Figure 7 is a transverse section, on a reduced scale, of an electric plug formed according to an embodiment of this invention, having a wedging member of a modified construction;

Figure 8 is a bottom perspective view of the modified wedging member employed in the electric plug shown in Figure 7.

Referring to the drawings, the numeral 10

2

designates generally an electric plug constructed according to an embodiment of this invention, having a novel means for removably securing the wires of an electric cord to the contact terminals of the electric plug. The wires of the electric cord are adapted to be removably secured to the blades or prongs of the electric plug in a manner whereby the electric wires may be removed or inserted at will, the structure of the electric plug 10 and a cover member providing for the locking and clamping engagement of the clamping elements, to be described hereinafter, whereby the electric wires are secured clamped in the plug and to their respective prongs or blades.

The electric plug 10 comprises an insulated cup-shaped body 11, open at its upper end to provide for extension of the connecting prongs or blades 12 and 14 from the upper open end thereof. The body 11 is formed with a pair of segmental, arcuate shoulders 15 on the inside wall thereof for supporting the prongs 12 and 14 in their fixed position within the body.

The contact plate 16 is fixed to or formed integrally with the lower end of each of the prongs 12 and 14, and as each of the prongs 12 and 14 is formed in substantially the same manner, the description of one of the prongs with its contact plate will suffice for description of the other.

The contact plate 16 is formed integrally with or otherwise suitably secured to the extreme lower end of the prong 12 and is formed as a segmental, arcuate plate and disposed at right angles to the length of the flat bar 17 which forms the prong 12. The outer edge 18 of the flat plate 16 is formed on an arc substantially the same as the curvature of that portion of the body 11 with which the outer edge 18 is adapted to be positioned in contact. A hole 19 is formed in the end of the plate 16 adjacent to the lower end of the prong 12 and is provided for the insertion of a fastening element, as a screw or rivet, for securing the plate 16 within the body 11. The body 11 is formed with a reinforcing strut 20 terminating downwardly from the extreme upper edge of the upper open end of the body 11. The plate 16 is adapted to be seated, at one end, on the rib 20, and a bolt or rivet, not shown in the drawings, is adapted to be extended through the hole 19 and threadably engaged in the strut 20 for fixedly securing the plate 16 within the body.

In Figures 1 and 2 of the drawings, the reinforcing strut 20 is formed integrally with the body 11 and extends upwardly to the extreme upper edge thereof, and these figures are meant to exemplify the formation of the plug 10 wherein the prongs 12 and 14 and their respective plates 16 are formed integrally with or molded in the formation of the plug body 11. In such instances, no screw or rivet will be employed for securing the plate 16 to the body.

A second hole 21 is formed in the plate 16 and is provided for receiving a wire 22 of an electric cord 24. A third hole 25 is formed in the end of the plate 16 opposite the hole 19 and is provided as a pivot aperture for receiving the pivot pin of a clamping wedge which is pivotally supported on the plate 16. When the prong 12 is used on a plug 10 wherein the upstanding strut 20 extends above the plate 16, as shown in Figures 1 and 2 of the drawings, and where the prong 12 and plate 16 are secured in the molded body 11, the strut 20 above the plate 16 will constitute a stop member or lug spaced outwardly from the bar 17 of the prong 12 to define a channel 26 through which the wire 22 is engaged, as the wire is led to the clamping element carried by the plate 16. In instances where the plate 16 is secured in the body 11 by a bolt or rivet extending through the aperture 19, a separate lug 27 is fixed to or formed integrally with the plate 16 on the edge opposite the bar 17 to define a channel 28 similar to the channel 26, through which the wire 22 is engaged.

A clamping element 29 is pivotally secured on each of the plates 16 and is formed of a substantially triangular metal or conducting plate 30. The plate 30 is formed with a straight longitudinally-extending inside edge 31 and a right-angularly-disposed rear edge 32. The outside edge 34, which connects the extremities of the edges 31 and 32, is substantially arcuate in configuration, as clearly shown in Figures 1 and 4 of the drawings, and the rear end portion of the outside edge 34 adjacent the rear edge 32 is upturned to form an upturned guide element 35 for slidably engaging the clamping member 29 over the wire 22 when the clamping element 29 is swung from its open to its closed position. The closed position of the clamping element 29 is clearly shown in the upper portion of Figure 1 of the drawings, and the open position of the other clamping element is shown in the lower left portion of Figure 1. A pivot pin 36 is fixed to or formed on the lower side of the plate 30 at the juncture of the sides 31 and 34, substantially the apex of the triangular plate, and the pivot pin 36 is adapted to be rotatably extended through the hole 25 of the clamping plate 16.

The length of the clamping member 29 is substantially shorter than the length of the clamping plate 16 or contact terminal, and the rear edge 32 of the clamping member 29 is adapted to be slidably engaged in a notch 37 formed on the lower end of the prong 12 adjacent the plate 16.

The clamping members 29 are adapted to be pivotally secured on their respective clamping plates 16 prior to the installation of the prongs 12 and clamping plates in the body 11. Upon engagement of the pivot pins 36 through the holes 25, the lower ends of the pivot pins 36 may be upset, as clearly shown in Figure 2 of the drawings, for holding the pivots in the holes. The loose engagement of the pivot pin 36 in the aperture 25 provides for a slight vertical swinging movement of the outer edge 32 vertically relative to the inner end or apex of the triangular plate when the clamping member 29 is engaged over the wire 22. In all pivoted positions of the clamping member 29, about the pivot pin 36 thereof, the edge 32 is engaged in the notch 37 in the prong 12. The upper edge 38 of the notch 37 provides a bearing surface for the upper side of the clamping member 29 for holding the clamping member against upward movement when

the clamping member is slidably engaged over a wire, as the wire 22. A kerf 39 is formed along the upper edge of each of the clamping members 29 transversely thereof, and extending substantially across the pivot pin 36, whereby a screw-driver or similar instrument, may be engaged in the kerf 39 for rotating the clamping element 29 from its open to its closed position for clampingly engaging the wire 22 between the clamping element 29 and the conducting plates 16. Together, the prongs 12, the conducting plates 16 and the clamping members 29 constitute the terminals 40 and 41 of the plug 10.

An insulated cover plate 42 is formed for sliding engagement over the contact prongs 12 and 14 for closing the upper, open end of the body 11. The cover plate 42 is formed of a disc 44 formed of suitable insulated material having a pair of slots through which the prongs 12 and 14 are adapted to be freely extended. The outside diameter of the disc 44 is substantially equal to the inside diameter of the upper open end of the body 11, and the lower surface of the disc 44 is adapted to be seated on a peripheral rib or ridge 47 extending about the periphery of the upper open end of the body 11, spaced downwardly a short distance from the upper end of the body, as clearly shown in Figure 2 of the drawings. A bridge element 48 is fixed to or carried by the lower surface of the disc 44 and is formed for holding the wires 22 in spaced-apart relation within the body 11 and for holding the clamping members 29 in their overlying, clamping position relative to the conducting plates 16. The bridging element 48 is substantially U-shaped in configuration, having a horizontal bight portion 49 which is adapted to be secured or otherwise fixed to the lower surface of the disc 42 and a pair of depending lugs 50 and 51 for engagement with the longitudinal edges 31 of the clamping members 29 in the clamping position of the clamping members.

In Figures 7 and 8, a pivot pin 52 is fixed to or formed on the contact clamping member 29 slightly different from the pivot pin 36 described above. The pivot pin 52 is formed of an elongated shank 54 which projects substantially at right angles from the lower surface of the plate 30 and has a forwardly extending horizontal arm 55 on the lower end of the shank 54. The pin 52 is not upset in the same manner as the pin 36, since the arm 55 will hold the pivot pin 52 in the hole 25 in the plate 16. The engagement of the pivot pin 52 through a conducting and clamping plate 16 is shown in Figure 7 of the drawings, wherein the horizontally-extending arm 55 is disposed below the lower surface of the plate 16, and the horizontal portion 55 acts in substantially the same manner as the upset end of the pin 36 for holding the plate 29 against accidental or inadvertent upward movement at its pivoted end.

In the use and operation of the electric plug 10, the electric cord 24 is initially extended through an aperture or opening 56 in the bottom of the body 11 with the cover 42 removed. The wires 22 are separated, and each of the wires is extended for engagement with one of the terminals 40 and 41. The wires 22 are extended through the channels 26 or 28 and the bare wire 22 is then extended downwardly through the wire-receiving hole 21. The clamping member 29 is then swung to an overlying position relative to its respective plate 16 for overlying both the plate and the wire 22 engaged thereon. As

the clamping plate 30 is engaged over the wire 22, the upturned edge 35 will provide for the free sliding of the plate 30 over the wire and the wire will bias the plate 30 upwardly as provided for by the looseness of the pin 36 engaging in the hole 25. The upper edge 38 of the notch 37 will prevent the excessive upward swinging movement of the plate 30, so that when the clamping member 29 is rotated about its pivot pin to put the outside edge 34 in engagement with the inside edge of the body 11, the wire 22 will be securely clamped between the clamping member 29 and the underlying contact plate 16. The cover 42 is then slid downwardly along the length of the prongs 12 and 14 so that the lugs 50 and 51 extend downwardly below the contact plates 16 on the opposite sides of the body 11, and the outside edges of the lugs 50 and 51 engage the longitudinal edges 31 of the clamping members 29 for holding the clamping members against inadvertent or accidental swinging movement about their pivots 36. The engagement of the lugs 50 and 51 of the bridge 48 within the body 11 with the longitudinal edges 31 of the clamping plates 29 is shown in dotted lines in Figure 1 of the drawings.

I do not mean to confine myself to the exact details of construction herein disclosed, but claim all variations falling within the purview of the appended claims.

I claim:

1. A connector plug comprising a cup-shaped insulating body having an open upper end, a contact member having a contact plate fixedly supported within said body and a blade projecting upwardly therefrom and extending upwardly beyond the upper end of the body, a clamping plate loosely pivoted on a vertical axis to said contact plate and arranged to be swung from an inoperative position at one side of said contact plate to an operative position overlying said contact plate to clamp a wire between said contact

plate and said clamping plate in which said clamping plate is tilted into parallelism with said contact plate, a cover comprising a disk engageable with the upper end of said body above said clamping plate, said disk being formed with an opening passing said blade, a fixed lug depending from said disk to engage an edge of said clamping plate in the operative position of said clamping plate whereby pivoting of said clamping plate out of operative position is precluded.

2. A connector plug comprising a cup-shaped insulating body having an open upper end, a contact member having a contact plate fixedly supported within said body and a blade projecting upwardly therefrom and extending upwardly beyond the upper end of the body, a clamping plate loosely pivoted on a vertical axis to said contact plate and arranged to be swung from an inoperative position at one side of said contact plate to an operative position overlying said contact plate to clamp a wire between said contact plate and said clamping plate in which said clamping plate is tilted into parallelism with said contact plate, said clamping plate having an upstanding edge arranged to slide on the upper surface of said contact plate as said clamping plate is swung into operative position, said upstanding edge serving to guide a wire into clamping position on said contact plate as said clamping plate is pivoted into operative position.
